UNITED STATES PATENT OFFICE.

JULIUS HIRSH, OF PHILADELPHIA, PENNSYLVANIA, ASSIGNOR TO HIMSELF AND JOSEPH BEHAL, OF SAME PLACE.

DESIGN FOR AN UNDERGARMENT.

SPECIFICATION forming part of Design No. 27,408, dated July 20, 1897.

Application filed May 8, 1897. Serial No. 635,744. Term of patent 7 years.

To all whom it may concern:

Be it known that I, JULIUS HIRSH, a citizen of the United States, residing in Philadelphia, Pennsylvania, have invented a new 5 and original Design for an Undergarment, of which the following is a specification.

My design for an undergarment is shown in the accompanying drawing.

The design relates to the upper portion of 10 the front of the garment, the leading feature of the design being the double scallops or festoons presented by the lower edges of the front shoulder or breast portions of the garment.

15 The shoulder portions of the garment overlap the front body or breast portion and the double scalloped or festooned lower edges of said shoulder portions lie loosely upon the body or breast portion of the garment. These

shoulder portions of the garment are represented at 1 and 2, the scallops of the portion 1 being shown at 3 and 4 and those of the portion 2 being represented at 5 and 6.

The neck portion of the garment and the edges of the scallops may be ornamented in 25 any desirable way, such ornamentation forming no essential part of my design.

I claim—

The design for an undergarment, substantially as described and shown in the accompanying drawing.

In testimony whereof I have signed my name to this specification in the presence of two subscribing witnesses.

JULIUS HIRSH.
